UNITED STATES PATENT OFFICE.

JOHN W. BURGESS AND GEORGE F. BURGESS, OF KANSAS CITY, MISSOURI.

INNER TIRE-CUSHION.

1,375,032.

Specification of Letters Patent. Patented Apr. 19, 1921.

Application filed August 9, 1920. Serial No. 402,232.

To all whom it may concern:

Be it known that we, JOHN W. BURGESS and GEORGE F. BURGESS, citizens of the United States, residing at Kansas City, in the county of Jackson, State of Missouri, have invented a new and useful Inner Tire-Cushion, of which the following is a specification.

The device forming the subject matter of this application is a filler for tire casings, so constructed that pneumatic elements, subject to puncture and deterioration, may be dispensed with, and the present invention aims so to construct the filler that the same will have the necessary resiliency, combined with stability to resist lateral strains.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in cross section, a device constructed in accordance with the invention; Fig. 2 is a section on the line 2—2 of Fig. 1; and Fig. 3 is a section on the line 3—3 of Fig. 1.

The numeral 1 denotes a rim on which is mounted a casing 2. Within the casing is located a filler preferably made of a plurality of blocks 3, placed in end to end abutment, the blocks conforming to the cross sectional contour of the casing 2 and being made, ordinarily, of rubber or other resilient material. The blocks 3 are inclosed within a tread band 4, the band 4 ordinarily being made of canvas or other relatively inelastic material. The band 4 is endless, and tends to limit the outward or centrifugal movement of the blocks 3. Each block 3 is pro-

vided with one or more radial bores 5, extended part way through the block, from the inner edge of the block toward the outer edge of the block thereof. Each block is provided, in its median plane with a slit 6 of less width than the bores 5, the slit intersecting the bores and being of substantially the same depth as the bores. When the blocks 3 are placed in end to end abutment in the casing 2, the slits 6 of the blocks are alined, as shown clearly in Fig. 3 of the drawings.

The general construction of the device is such that it will possess the necessary resiliency, combined with stability to resist lateral strains.

The blocks 3 may be of any desired length. They are placed in the casing 2 until the casing is filled, circumferentially. Then, by compressing the blocks longitudinally, they may be expanded transversely, or "fattened", thereby pulling the casing tightly and completely.

If desired, a strip of asbestos or other refractory material, denoted by the numeral 25, may be placed in the slit 6, to prevent the slit from closing together, the strip 25 serving to prevent an overheating of the tire, due to friction. The strip 25 does not fill the slit 6 completely, the major portion of the slit being open, adjacent to the axis of the filler.

Having thus described the invention, what is claimed is:—

A tire filler having radial bores extended part way therethrough from the inner edge thereof toward the outer edge thereof, and provided in its median plane with a slit of less width than the bores, the slit intersecting the bores and being of substantially the same depth as the bores.

In testimony that we claim the foregoing as our own, we have hereto affixed our signatures in the presence of two witnesses.

JOHN W. BURGESS.
GEORGE F. BURGESS.

Witnesses:

T. P. CHAPMAN,
E. STEPHENSON.
